UNITED STATES PATENT OFFICE.

ELI T. STARR, OF PHILADELPHIA, PENNSYLVANIA.

IMPROVED VULCANIZING-FLASK FOR DENTISTS.

Specification forming part of Letters Patent No. 57,210, dated August 14, 1866.

To all whom it may concern:

Be it known that I, ELI T. STARR, of the city and county of Philadelphia, in the State of Pennsylvania, have invented certain new and useful Improvements in Vulcanizing-Flasks for Dentists' Use; and I do hereby declare that the following is a full, clear, and exact description of the same, reference being had to the accompanying drawings, making a part of this specification, in which—

Figure 1 is a plan or top view. Fig. 2 is an inverted plan view. Fig. 3 is a central vertical transverse section. Fig. 4 is a partial side view.

Similar letters of reference indicate corresponding parts in all the figures.

The flasks heretofore employed by dentists for molding and vulcanizing rubber-work have been open to the objection that when their lower portions have been made of the proper depth for molding whole dentures, in which the line of division between the two portions of the mold is required at the rim of the plate, they have been too shallow for properly molding those artificial gums that are designed to rest upon the natural gums when placed in the mouth, inasmuch as in this case the line of division should be at the crowns of the teeth, which brings the plaster too high above the rim of the flask and affords too little support to the teeth when the two parts of the flask are brought together.

This invention is designed to remedy the above-mentioned defect, and also to provide for the more secure retention of the plaster in the flask, and to enable the different parts of the flask to be taken apart more conveniently than those heretofore devised; and it consists in certain novel means whereby the desired object is obtained.

To enable others to understand the nature and construction of my invention, I will proceed to describe it with reference to the drawings.

A and B represent two rings of the same shape and circumference, which are fitted together when the flask is used, as more clearly shown in Figs. 3 and 4, there being two spurs, *a*, upon opposite sides of the circumference of the part B, the said spurs fitting into holes or notches formed in corresponding lugs *b*, formed

upon the circumference of the other portion, A. One part of the circumference of these rings may be made nearly straight, as shown at *c c* in Figs. 1 and 2, while the opposite part is rounded or curved, to nearly or quite correspond with the rounded portion of the circumference of a plate of teeth. The outer edges of these rings A B converge inward somewhat, as shown in Fig. 3, and upon the outer side or edges of the plate A is placed a covering-plate, *d*, and upon the corresponding outer side of the ring B is placed another covering-plate, *e*. These rings A B and plates *d e*, when secured together, as will be presently explained, constitute the body of the flask.

The rings A and B are of unequal width, the width of the ring A corresponding to the flask for molding whole dentures, in which the line of division between the upper and lower portions of the mold is required to be at the rim of the plate, while the width of the other ring, B, corresponds to the depth required in the said lower portion of the flask when used for molding those gums which are intended, when placed in the mouth, to rest upon the natural gums, in which case it is necessary that the line of division should be at the crowns of the teeth, it being designed to use one ring or the other for the lower portion of the flask, according to the variety of work to be molded therein.

The plate *d* is provided with several holes, *f*, which are beveled or countersunk at their outer ends, so that when the semi-fluid plaster is poured into the flask a portion flows into the said holes and fills them, together with their countersunk outer ends, so that on cooling the mass of plaster is firmly held therein.

The plates *d* and *e*, being of the same size and shape, are interchangeable, so that the plate *d* may be used upon either of the rings A B, as may be desired.

Formed at suitable points upon the circumference of the covering-plate *d* are any required number of laterally-projecting lugs, *g*, in the outer surface of which are formed oblong recesses *h*, which correspond to the shape and size of the heads *i* of the T-bolts *j*, and formed in the outer edges of the lugs *g* are deep notches or slots *n*, which extend inward to the inner sides of the recesses *h*. Formed upon the circumference of the other covering-plate, *e*, op-

posite the lugs *g* when the flask is closed, are corresponding lugs *k*, in each of which is formed a vertical hole, of such size as to allow the screw or threaded end of one of the bolts *j* to pass through it, as more clearly represented in Fig. 4.

The T-bolts *j* are placed with their heads *i* in the recesses *h* of the lugs *g*, and pass through the slots *n* in the said lugs and through holes in the lugs *k*, and are provided upon their threaded ends, outside of the said lugs *k*, with nuts *r*, so that by tightening the said nuts *r* the rings *A* *B* and plates *d* *e* are tightly and securely held together, thus constituting the flasks in a closed condition, while, by loosening or unscrewing the said nuts for a short distance, the said bolts may be pushed upward or inward, so as to bring the heads *i* out of the recesses *h*, and allow the headed ends of the bolts to be pushed out laterally through and from the slots *n*, thus enabling the several parts of the flask to be taken apart without removing the nuts *r* from the bolts *j*, and avoiding, in a great degree, the expenditure of time and trouble required in opening the flask by separately and entirely removing the clamping bolts therefrom, as in the ordinary way.

The mold is formed within the flask by means of plaster-of-paris in the usual manner, and the flask is also employed in the vulcanizing pro-

cess in the same manner as the common flask, one or the other of the rings *A* *B* being used to form the lower portion of the flask, and the plate *d* being used upon one or the other ring, as may be desired, all as hereinbefore fully explained, and the plaster adjacent to the plate *d* being securely held in place by that portion thereof projecting into and retained by the countersunk holes *f* in the said plate, and the several parts of the flask being held together by the T-bolts, extending from the lugs *g* to the lugs *k*, as set forth.

What I claim as new, and desire to secure by Letters Patent, is—

1. The combination of the two rings *A* *B* and interchangeable plates *s* *e*, substantially as herein set forth, for the purpose specified.
2. The holes *f*, beveled or countersunk at their outer ends, in combination with the covering-plate *A* and a ring, *A* or *B*, substantially as herein set forth, for the purpose specified.
3. The slotted lugs *g*, recessed as described, of the plate *s*, in combination with the T-bolts *j*, nuts *r*, and perforated lugs *k* of the plate *e*, substantially as herein set forth, for the purpose specified.
